CLAIM

The ornamental design for a combined calf and foot massager, as shown and described.

DESCRIPTION

FIG. 1 is a perspective view of a combined calf and foot massager showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are for the purpose of illustrating portions of the combined calf and foot massager, which form no part of the claimed design.

1 Claim, 7 Drawing Sheets
